UNITED STATES PATENT OFFICE.

HARRISON J. MITCHELL, OF SEATTLE, WASHINGTON, ASSIGNOR TO WILLIAM H. PAYNE, OF SEATTLE, WASHINGTON.

INSTRUMENT FOR MARKING MOLDING CUTTERS OR BITS.

Application filed October 13, 1921. Serial No. 507,499.

To all whom it may concern:

Be it known that I, HARRISON J. MITCHELL, a citizen of the United States, residing at Seattle, in the county of King and State of Washington, have invented certain new and useful Improvements in Instruments for Marking Molding Cutters or Bits, of which the following is a specification.

This invention relates to instruments for marking upon cutter bits or the like lines to which they are to be ground or sharpened for producing predetermined shapes of moldings or similar articles on a planing machine.

Difficulty has hitherto been experienced in accurately marking out cutters of this character to a sharpening line which will afford a predetermined transverse shape by reason of the cutters being revolvably mounted on cutter heads in angular relations with respect to planes radial thereto. In order, therefore, to mark a blank for a cutter bit which will produce a molding having a selected curved or irregular outline it is essential that the contour or design of such outline on the blank be protracted longitudinally of the same.

The object of the present invention is the provision of a device for quickly and accurately describing upon cutter bits grinding lines of suitable curvature and proportions for accomplishing the function above referred to.

The invention consists, generally, of a manually operated instrument having a travelling trammel-beam which carries by one of its arms a bit marking stylus whose movements are controlled by means of a tracing point carried by its other arm cooperating with a pattern having a shape similar to the transverse section of the article which the finished cutter bit is intended to produce.

The invention further consists in the novel construction, adaptation and combination of parts hereinafter described and claimed.

In the accompanying drawings,—

Figure 1 is a plan view of an instrument embodying my invention. Fig. 2 is a front elevation of the same. Fig. 3 is an end elevation taken at the right hand side of Figs. 1 and 2. Fig. 4 is a sectional view through 4—4 of Fig. 2. Fig. 5 is an end

elevation of a type of cutter head commonly used in wood planing machines. Fig. 6 is a perspective view of a work positioning plate, shown detached.

The invention comprises a rigid frame which, as shown in the drawings, includes a base member or table 10 provided with a plane upper surface 11 and having at each of its ends an upwardly extending standard 60 or post 12. Also included in said frame is a horizontal bar 13, preferably circular, disposed longitudinally of the frame and is engaged in bracket pieces 14 which are respectively secured to said posts and bar, as by means of set screws 15 and 16. Mounted 65 for longitudinal and rotary movements on the frame bar 13 is a relatively long sleeve 17 to which is rigidly secured a forwardly directed arm 18 and together constitute what will hereinafter be designated as the 70 carriage. Swiveled by means of a pin 19 to the carriage arm 18 for horizontal rotary movements is a yoke 19 having an aperture 20, Fig. 4, to receive a horizontally disposed trammel beam 21.

As illustrated said yoke is provided with a horizontal slot 22 which extends from an end thereof to beyond the aperture 20 to afford bifurcations which serve through the medium of a screw 23 to clamp said yoke to 85 the beam 21. Said slot also furnishes a way for a spline 24 provided in the beam to obviate any rotary movement of the latter with respect to the yoke.

Adjustably secured, as by screws 25 and 90 26, to the beam at opposite sides of said yoke are attachments 27 and 28. The attachment 27 is provided with a socket for a vertical rod or tracer 29 having a sharp lower extremity. The other attachment, 28, is provided with a vertically disposed screw threaded hole within which is engaged an exteriorly threaded tubular holder 30 for a pencil or stylus 30¹, said holder being provided with a head 31 to facilitate the adjustment of the same.

The lower end of said holder is desirably slotted so as to be brought into clamping relations with the stylus by means of a nut 32 having a tapered aperture.

The table 10 is provided with a longitudinal groove 33 for the reception of a plate 34 having a serrated edge 35 protruding above the plane of the table to engage in transversely arranged corrugations 36, Fig. 110

3, provided in the under side of a certain type of cutter bits, as shown with respect to the blank 37 in Fig. 3. For detachably retaining a blank firmly upon the base member 5 I provide clamping means in the nature of a spring-metal blade 38 which is secured at one of its ends to a bracket rod 39 which, in turn, is secured by means of a screw 41 in a coupling block 40 provided on the adjacent frame post 12.

A second plate 34¹ is advantageously employed in the frame groove 33 to serve as a backing for positioning a pattern; as 43 for example, upon the table and upon which, the 15 pattern is held by means of a spring blade 38¹ which is connected to the adjacent frame post through the medium of a bracket rod 39¹, block 40 and screw 41¹.

In Fig. 5, I show a cutter head 45 of an 20 ordinary type to illustrate the relations of the bits 37^a which are carried thereby with respect to the axis of the head spindle.

In operation, the work or bit 37 and the 25 pattern 43 are placed upon the frame to have the stylus and tracing elements, when in vertical position, register therewith. The trammel is tiltably movable about the axis of the bar 13 and, for convenience in setting, the sleeve 17 of the carriage is provided on 30 its periphery with an index mark 51 to register with a guide line 50 on the bar 13 when the carriage is in position to retain the stylus and tracing point vertical. The yoke 19 is then temporarily disengaged from the trammel beam and the carriage shifted, if necessary, to have the beam arms of lengths, proportionally of each other, to suit the angular relations at which the cutter bit is to be applied to a head with respect to a plane radial 35 of the head's axis.

The beam is advantageously provided with angle indicating marks 47, Fig. 1, to facilitate such adjustments of the beam with respect to the yoke.

45 With the beam thus arranged, the operator causes the tracing point to follow the outline, as *a*, of the pattern 43 thereby influencing the beam and carriage to carry the stylus upon the bit to mark the same, as at 50 *b*.

The travel of the carriage produces similar movements of the tracer and stylus longitudinally of the instrument; and the pivotal connection of the yoke to the carriage affords movements of the tracer and stylus transversely to the travel of the carriage with an amplifying ratio proportional 55 to the lengths of the beam arms one to the other.

60 The construction and operation of the invention will, it is thought, be understood from the foregoing.

What I claim is:

1. In an instrument of the character described, the combination with a frame, of a

carriage arranged for movements longitudinally of said frame, a trammel beam pivotally connected intermediate its length to said carriage for movements parallel and in angular relations with respect to the direction of the carriage travel, a stylus carried by one arm of said beam, and a pattern tracing point carried by the other arm of the beam.

2. In an instrument of the character described, the combination with a frame having a table member, and a horizontal bar element in spaced relations above said table, of a carriage mounted on the frame bar to travel longitudinally of the frame, a yoke connected for rotation about a vertical axis to said carriage, a rod extending horizontally through said yoke, means provided on the yoke for securing the rod thereto at selected adjustments longitudinally of the rod and with respect to its axis of its rotation, a tracing point carried by the rod adjacent to one end thereof, and a stylus carried by the rod adjacent to its other end.

3. In an instrument of the character described, the combination with a frame having a table member provided with a slot longitudinal thereof, said frame including a horizontal bar element in spaced relations above said table, of a carriage mounted on the frame bar to travel longitudinally of the frame, a yoke pivotally connected to said carriage, a rod extending horizontally through said yoke, a tracing point carried by the rod adjacent to one end thereof, a stylus carried by the rod adjacent to its other end, and means provided in said slot for positioning a pattern and a blank upon said table in operative relations with respect to said tracing point and the stylus.

4. In an instrument of the character described, the combination with a frame having a table member and a horizontal bar element in spaced relations above said table, of a carriage mounted on the frame bar to travel longitudinally of the frame, a yoke pivotally connected to said carriage for horizontal rotary movements, a rod extending horizontally through said yoke, means for securing the rod to the yoke at selected adjustments axially of the rod, a tracing point carried by the rod adjacent to one end thereof, and a stylus carried by the rod adjacent to its other end.

5. In an instrument of the character described, the combination with a frame having a table member provided with a slot longitudinal thereof, of a carriage mounted on the frame to travel longitudinally thereof, a yoke pivotally connected to said carriage, a rod extending horizontally through said yoke, means provided on the yoke for securing the rod thereto at selected adjustments axially of the rod, a tracing point carried by the rod adjacent to one end thereof, a

stylus carried by the rod adjacent to its other end, and means provided in said slot for positioning a pattern and a blank upon said table in operative relations with respect to said tracing point and the stylus.

6. In an instrument of the character described, the combination with a frame, a carriage mounted thereon for relative longitudinal travel, a trammel having a swivel connection intermediate its length to said carriage, said trammel having a tracing element at one end and a marking element at its other end, said elements being disposed in relation to said pivotal connection to afford amplified movements of the marking element with respect to the tracing element for movements transverse to the travel of said carriage.

7. In an instrument of the character described, a support for a pattern and the

work, a frame, a carriage mounted upon said frame for movement longitudinally of said support, a trammel bar having a swivel connection to said carriage and adapted to be adjustably moved endwise thereof, a work-marker connected to one end of said bar and a pattern-tracer connected to the other end of the bar whereby the marker and tracer are caused to be carried with said carriage in the travel of the latter and are revoluble with the bar about the pivotal connection of the latter with the carriage and independently of the carriage when the same is stationary.

Signed at Seattle, Washington, this 29th day of September, 1921.

HARRISON J. MITCHELL.
